UNITED STATES PATENT OFFICE.

JULIUS G. HEINICKE, OF RICHMOND HILL, NEW YORK.

DISPLAY-BOX.

1,016,148.

Specification of Letters Patent.

Patented Jan. 30, 1912.

Application filed July 26, 1911. Serial No. 640,633.

To all whom it may concern:

Be it known that I, JULIUS G. HEINICKE, a citizen of the United States, residing at Richmond Hill, in the county of Queens and 5 State of New York, have invented new and useful Improvements in Display-Boxes, of which the following is a specification.

My invention relates to a box, or container, for small articles, such as tubes of 10 tooth paste, bottles of perfumery etc., designed to be made of a single piece of cardboard or similar material, stamped or cut in the desired form and then easily folded to shape.

15 The container is double, that is composed of two receptacles, united at one vertical edge, so that they can be arranged at an angle to each other to stand upright on the counter. Each receptacle is provided with a 20 front opening, sufficiently large to exhibit the contained articles, but not large enough to permit them to be removed from the front. The receptacles have top openings, closed by 25 folds folding back from the front, so that the articles may be removed easily from behind.

This container is convenient for shipping the articles and then for the display thereof in the shop, where the container is set on 30 edge and the two receptacles arranged at an angle, so as to stand on end without rear props etc. The articles are well displayed but not conveniently removed from the front, so that theft is discouraged. But the 35 articles may be removed conveniently from the rear, that is by the clerk behind the counter. The container so formed is strong, simple and economical to manufacture—convenient for shipping and for display as 40 aforesaid.

My invention is shown in the drawing herewith in which the reference characters of this description indicate the corresponding parts in all the figures.

45 Figure 1 shows the one piece blank, as stamped and ready to be folded to form the complete container. The creases for the folds are indicated in dotted lines. Fig. 2 is a perspective view of the container in display position. Fig. 3 is a horizontal section of Fig. 2. Fig. 4 is a vertical section of one of the receptacles. Fig. 5 is a horizontal section of the receptacle folded for shipping.

55 In Fig. 1 is shown the blank of card board, which may be stamped at one operation, with a die of desirable form, and is then

folded to form the two receptacles A A, connected by a hinge connection 1 at the vertical front edge. Each receptacle consists of the front 2, having the display opening 3, the back 4 connected to the front by the outer end 5, said end having a top flap 6 to be folded down and in; the inner end 8 on the inner edge 9 of the back 4, having the end fold 10, to be folded in and forward and gummed to the rear surface of the front adjacent to the hinged connection, or crease, 1, said inner end having a top flap 11 to be folded down and in; the top 12, extending from the upper edge 13 of the front 2 and having the top fold 14 to be folded back and down and tucked within the back 4; and the bottom 16, extending from the lower edge 17 of the back 4 and having the bottom fold 18, to be folded forward and up and tucked within the lower portion of the front; the bottom is desirably provided with the flaps 20 and 21 to be folded up and tucked inside respectively of the inner end 8 and the outer end 5. The bottom fold 18 may be secured by adhesive gum to the rear surface of the front but this is not usually necessary. This description sufficiently describes the form of the blank and the manner in which the various portions are folded along the creases to 50 inclose the collapsible tubes 25 or other articles. Better to protect such articles, one from the other, a stiffening piece 26 may be inserted in each receptacle back of the articles with integral flaps 27 extending between 55 the same. On the left of Fig. 2 the flaps are so arranged; on the right, they are shown folded back so as to be out of sight when the articles are replaced.

When the receptacles are folded face to 60 face as in Fig. 3 for shipping, the flat insert 30 may be placed between the adjacent fronts of the two. The front edges of the flaps engage with this insert, whereby the whole container is further reinforced and 65 stiffened. In the position of Fig. 3, the backs, ends, tops and bottoms are exposed to view, and may carry suitable addresses, advertising matter or other inscriptions or 70 signs.

In Fig. 2 is shown the position of the container on the counter. The tops need not be folded down snugly but may be held up in the position shown by the flaps 6 and 11 to act as a "headline" for the name of 75 the article in large letters, or some other conspicuous inscription.

When, in retail trade, all the articles in one receptacle have been sold, that receptacle may be torn off along the crease 1, leaving the other complete and full. Or 5 when desired to utilize one receptacle separately, as for selling the half dozen articles therein, it may be separated along said crease and a cover 35 set over the front to make a complete package, as indicated in 10 Fig. 4 by dotted lines.

Having described my invention, I claim,
A container for small articles comprising
a receptacle having a top opening to admit
the articles, a top cover fold for the top
15 opening arranged to fold back from the

front of the receptacle and to be opened from the rear, obstructing access to the articles from the front but permitting withdrawal thereof from the rear, said receptacle front having a display opening of a size 20 to exhibit the greater portion of the displayed articles but to prevent withdrawal of the articles therethrough.

In testimony whereof I have signed my name to this specification in the presence of 25 two subscribing witnesses.

JULIUS G. HEINICKE.
